UNITED STATES PATENT OFFICE

FRANK CENZI, OF ST. LOUIS, MISSOURI

DRIER FOR DOUGH PRODUCTS

Application filed February 9, 1928. Serial No. 253,002.

This invention pertains to driers for noodles and similar dough products.

One of the objects of this invention is to provide a device in which the product may be quickly and thoroughly dried in a simple and effective manner.

Another object is to provide means whereby the product may be given an extended travel while subjected to a draft of air.

10 Further objects will appear from the following description, taken in connection with the accompanying drawings, in which—

Figure 1 is a plan view of a drier embodying this invention;

Figure 2 is a side elevation of the same;

Figure 3 is a section on line 3—3 of Figure 1;

Figure 4 is a detail section on line 4—4 of Figure 3;

Figure 5 is a perspective detail of Figure 4; and

Figure 6 is an enlarged detail of Figure 1.

Referring to the drawing, I designate a 25 supporting frame or base. Mounted for oscillating movement upon the base 1 is a series of trays 2 and 3. Each is constructed with an outer frame 40 provided with guide rails 41 adapted to receive an inner frame 42 upon 30 which is stretched a screen or perforated bottom 22. The screen or bottom 22 is thus removably mounted in the outer frame between the rails 41. In order to provide for removing the screen, the outer frame 40 is provided

35 with a removable end board 43, seated in grooves in the side pieces and secured in place by a clamping bolt 44. This provides for renewal of the screens when worn. When in place, the screens are secured by screws 45.

40 In this series alternate trays are rigidly connected together by straps 4 or other suitable means. The straps 4 connect the trays 2, while similar straps 5 connect the trays 3. Each group of trays is supported for oscillation on the base 1. Pivoted at 6 on said base are links

45 7, which are pivoted at their other ends 8 to one of the trays of group 3. This mounting permits an endwise oscillating movement for these trays. In a similar manner, links 9, 50 pivoted at 10 to one of the trays of group 2

and at 11 to the base 1, support the group 2 for similar oscillating movement.

The trays 3 are connected at the end of the machine by a bracket 12. This bracket has pivoted thereto at 13 a pitman 14 connected with an eccentric 15 on a shaft 16. One of the trays 2 has pivoted thereto at 17 a pair of pitmen 18, each of which connects with an eccentric 19 on the shaft 16. The eccentrics 15 and 19 are oppositely displaced on the shaft 16, so that, when said shaft is rotated, the pitmen 14 and 18 will impress upon the two groups of trays opposite oscillations. The shaft 16 carries a pulley 20 connected by a belt 21 to any suitable source of power, not shown.

The trays 2 and 3 are preferably constructed so that their bottoms 22 are arranged to slope in opposite directions in successive trays. For instance, in Figure 2, the bottom of the 70 upper tray slopes downwardly to the right, while that of the second tray slopes downwardly to the left, and so on, alternately throughout the stack. At the left-hand end of the upper tray, a box or hopper 23 may be 75 provided to receive the material as it is delivered to the drier. The discharge end of each tray is provided with a gap 24 between the termination of its bottom 22 and the end of the tray, so that the material, when it reaches that 80 end of the tray, will fall through the gap to the next tray beneath. The last tray 2 may be provided with an extension 25 for discharging the material.

Enclosed in the lower part of the frame 1 85 is a housing 26 providing an air compartment communicating at its upper portion with the stack of trays. The sides of the trays are formed with rabbet joints, as indicated at 27, 90 Figure 3, so as to permit relative movement thereof, while at the same time providing a substantially continuous side wall from bottom to top at each side of the stack of trays, thus providing together a vertical stack.

95 The housing 26 is provided at intervals therealong with lateral openings in which are mounted fans 28 mounted on shafts 29. The shafts 29 are belted together by belts 30 so as to run together, and one of these shafts 100

carries a pulley 31 connected by a belt 32 with a pulley 33 on the shaft 16.

The operation of this device is as follows: The shaft 16 having been set into rotation, the action of the eccentrics 15 and 19 through the pitmen 14 and 18 will oscillate the trays 2 and 3 in an endwise direction. These two groups of trays will oscillate in opposite directions. The shaft 16 also drives the fans 28, so as to set up a draft of air through the compartment 26 and upward through the stack of trays, the perforated bottoms permitting circulation of air upwardly therethrough. The material is fed into the device at the hopper 23, where it is deposited upon the bottom of the first tray. On account of the slope of the bottom, the oscillation of the tray will cause the material to move gradually toward the lower end thereof, after which it drops through the gap 24 to the next tray beneath. This tray, having its bottom sloped in the opposite direction, the material will travel back therealong to be delivered in a similar manner to the succeeding tray. In this manner, the material will travel successively through all the trays to be discharged eventually at the discharge end 25 of the last tray into any suitable receptacle, not shown. During its travel, the material is subjected to a continuous draft of air set up by the fans 28. As it travels along the different trays, it gradually becomes drier until it is finally discharged in the completely dry condition. It will be noted that the incoming air, which is dry, impinges first upon that part 35 of the material from which most of the moisture has been removed. As the air passes upwardly through the trays, it gathers moisture. Accordingly, the drier air is run into contact with the drier material. This arrangement promotes the rapid and complete drying of the material.

While this invention was designed particularly for drying noodles, it may be used for drying other dough products.

45 While the apparatus has been described as a unitary machine, it will be understood, of course, that certain combinations may be useful without other parts of the complete combination, and the use of such subcombinations 50 is contemplated by the invention. It is further obvious that various changes may be made, within the scope of the appended claims, in the details of construction without departing from the spirit of this invention; 55 it is to be understood, therefore, that this invention is not limited to the specific details shown and described.

Having thus described the invention, what is claimed is:

60 1. A drier for noodles and the like, comprising, a vertical stack of trays having perforated bottoms, the outside walls of said trays joining at their meeting edges so as to form 65 the outside walls of a vertical shaft, means

for shaking said trays, and means for passing air through said shaft.

2. A drier for noodles and the like, comprising, an enclosed frame having an air chamber therein, a vertical stack of trays 70 each having a perforated bottom and upright outside walls, the walls of said trays joining at their meeting edges so as to form the outside walls of a vertical shaft, means for blowing air into said chamber to pass upwardly 75 through said shaft, and means for oscillating said trays.

3. A drier for noodles and the like, comprising, an enclosed frame having an air chamber therein, a vertical stack of trays 80 each having a perforated bottom and upright outside walls, the walls of said trays joining at their meeting edges so as to form the outside walls of a vertical shaft, means for connecting alternate trays together to form 85 groups, means for blowing air into said chamber to pass upwardly through said shaft, and means for oscillating said groups.

4. A drier for noodles and the like, comprising, an enclosed frame having an air 90 chamber therein, a vertical stack of trays each having a perforated bottom and upright outside walls, the walls of said trays joining at their meeting edges so as to form the outside walls of a vertical shaft, means for connecting alternate trays together to form 95 groups, upstanding links pivoted on said frame and connected to support each of said groups for oscillating movement, means for blowing air into said chamber to pass upwardly through said shaft, and means for oscillating said groups.

5. A drier for noodles and the like, comprising, an enclosed frame having an air chamber therein, a vertical stack of trays each having a perforated bottom and upright outside walls, the walls of said trays joining at their meeting edges so as to form the outside walls of a vertical shaft, means for connecting alternate trays together to form groups, upstanding links pivoted on said frame and connected to support each of said groups for oscillating movement, means for blowing air into said chamber to pass upwardly through 105 said shaft, and means for oscillating said groups in opposite directions relatively to each other.

6. A drier for noodles and the like, comprising, a stack of trays arranged one above the other, means connecting together alternate trays of said stack to form a series of groups, with the trays of each group connected against relative movement and with the trays of one group interleaved with those of the other, means for mounting each group for endwise movement relative the other group, and means for reciprocating one group relative the other group.

7. A drier for noodles and the like, comprising,

ing, a stack of trays arranged one above the other, means connecting together alternate trays of said stack to form a series of groups, with the trays of each group connected against relative movement and with the trays of one group interleaved with those of the other, means for mounting each group for endwise movement relative the other group, and means for reciprocating said groups in opposite directions.

In testimony whereof I affix my signature this 27th day of January, 1928.

FRANK CENZI.
